UNITED STATES PATENT OFFICE.

WILLIAM PRESCOTT SHARP, OF COLUMBUS, OHIO.

APRON.

1,358,589.

Specification of Letters Patent. Patented Nov. 9, 1920.

Application filed April 11, 1919. Serial No. 289,304.

To all whom it may concern:

Be it known that I, WILLIAM PRESCOTT SHARP, a citizen of the United States, and a resident of Columbus, in the county of 5 Franklin and State of Ohio, have invented a new and Improved Apron, of which the following is a full, clear, and exact description.

It is a well-known fact that considerable 10 difficulty has been experienced in the applying of body garments, such as aprons, around the waistline, in that devices of this nature have been provided usually with tapes, buttons, or snap fasteners, which 15 fastening devices have been cumbersome, and particularly impracticable in view of their inaccessibility to the wearer.

My invention now contemplates the provision of an apron, or, in fact, any body 20 garment provided with a waistband adapted to encircle the waistline, to be combined with means for retaining such garment in applied position without the aid of any of the conventional fastening means.

25 A further object of this invention is to provide a garment of the aforementioned nature, which garment may be readily applied to the body and removed therefrom without the loss of any time.

30 A final object of this invention is to provide a device of this nature which shall combine certain members adapted to be incorporated with the garment and to be applied around the waistline, such members being 35 designed to clasp the waistline, however, without bearing too heavily against the body of the wearer.

Referring to the attached sheet of drawings which represent one practical embodiment of my invention, it will be seen that—

Figure 1 illustrates a side elevational view of an apron, with part of the waistline broken away to disclose the underlying attaching means whereby the garment is applied to the body;

Fig. 2 is a perspective view of such attaching means, and

Fig. 3 is a rear elevational view of the apron.

50 Briefly described, the invention includes an apron 1, of any convenient construction, provided with a waistband 2, comprising a tubular piece of material, whose ends extend beyond the edges of the apron, one of such 55 ends being left open as indicated at 3.

Through the open end 3 is inserted a band 4, comprising two circularly-extending strips 5 and 6, of semi-resilient material, and an interposed strip 7 of spring steel to which the inner ends of the strips 5 and 6 are 60 riveted, as indicated at 8, it being noted that the outer ends of the strips 5 and 6 overlap one another, as indicated at 9.

It will, of course, be understood that the arrangement of the band 4 may be varied 65 without departing from the scope of my invention. The reason for my constructing the band in the manner aforementioned, is that this arrangement apparently combines the greatest comfort to the wearer together 70 with economy of construction, the comfort being caused in view of the fact that the strips 5 and 6 are only semi-resilient and will not tend to too heavily engage the body of the wearer, in that the tension of the 75 spring steel piece 7, may be readily controlled at the time of manufacture.

In operation, it will be seen that the apron, or other body garment 1, may be applied to the body of the wearer by simply grasping 80 the waist-band overlying the strips 5 and 6 and pulling such points away from one another, whereupon the overlapping ends 9 will separate so that they may be passed around the body and released, when the band 4 will engage the body sufficiently to retain the garment 1 in applied position.

It will be appreciated that a bib or shoulder straps may be attached to the apron, or other body garment, by any suitable means 90 without in the least departing from the scope of this device.

Having now described my invention, what I desire to claim is:

1. A body garment, including a waist band and a resilient strip incorporated in said waist band, such resilient strip comprising a plurality of resilient and semi-resilient segments rigidly secured one to the other.

2. A body garment, including a waist band, a resilient strip incorporated in said waist band, said strip including a pair of semi-resilient segments, and a resilient section having rigidly secured to its ends the 100 inner ends of the semi-resilient segments.

WILLIAM PRESCOTT SHARP.
